UNITED STATES PATENT OFFICE.

HOWARD M. DUDLEY, OF PHILADELPHIA, PENNSYLVANIA.

DYEING-MACHINE.

1,258,544.

Specification of Letters Patent.

Patented Mar. 5, 1918.

Application filed December 29, 1916. Serial No. 139,453.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to a dyeing machine and refers particularly to a machine adapted for the dyeing of textile fibers compressed within a dyeing chamber, the dyeing being accomplished by the forced passage of the dye liquor through the fiber mass.

Among the objects of my invention is a dyeing machine particularly suitable for the dyeing of warps in the ball, whereby the condition of the fiber may be accurately and readily judged at any stage of the treatment without opening the dyeing chamber and whereby even results may be obtained without disturbing the fiber to be dyed.

Other objects of my invention will be evident upon a consideration of my specifications and claims.

I have found that the even or uneven dyeing results obtained in a machine of this general character depends largely upon the particular shape of the openings through which the dye liquor enters the fiber mass, and that unevenness can be prevented by the use of openings of a particular shape, the conformation of which enables the liquor to spread itself through the fiber mass without the formation of channels of flow.

I have further found that this desirable result can be obtained if such openings are of an elongated form, diverging upwardly into the dyeing chamber or of a double diverging conformation, diverging both upwardly into the dyeing chamber and downwardly into the source of dye liquor.

Related forms of my device are shown in the accompanying drawings, in which similar parts are designated by similar numerals.

Figure 1 is a side view of one form of my invention, partly broken away to disclose a portion in cross-section.

Fig. 2 is a cross-section through the line 50 2—2 of Fig. 1.

Fig. 3 is a side view of one of the plates introduced into the upper portion of the liquor supply chamber.

Fig. 4 is a side view of one of the plates

introduced into the lower portion of the liquor supply chamber.

Fig. 5 is a broken cross-section of a modification of the liquor supply chamber showing the plates extending from the bottom to the top thereof.

Fig. 6 is a cross-section of the pump chamber showing the plates extending downwardly therein.

Fig. 7 is a cross-section of a modification of the foraminous plate.

Fig. 8 is a top view of Fig. 7.

Fig. 9 is a cross-section of a modification of the foraminous plate.

Fig. 10 is a top view of Fig. 9.

The outer portion of the dyeing machine comprises the cylindrical shell 7 and the cylindrical shell 8, fixedly attached to each other by the bolts 9, 9; the conical shaped bell 10 fixedly attached to the shell 8 by the bolts 11, 11 and the centrifugal pump 12 fixedly attached to the shell 10 by the bolts 13, 13. A foraminous plate 14 is situated between the shells 7 and 8 and is integral with the wall of the chamber 8. The foraminous plate 14 is of a grate construction. The bars 16, 16 taper upwardly and downwardly from their center lines, forming diverged openings between them for the passage of liquor.

The machine is provided with a removable annular foraminous plate 17, the construction of which is similar to the foraminous plate 14.

An annular angle-shaped member 18, is slidable within the shell 7, capable of abutment upon the plate 17 and maintained in any desired position by means of the thumbscrews 19, 19, which thread within the shoulders 20, 20 fixedly attached to the shell 7.

A series of plates 21, 21 are positioned in the upper interior portion of the shell 10, the plates extending across the chamber formed by the shell, their upper and lower ends being tapered.

A series of plates 22, 22 are positioned in the lower interior portion of the shell 10, the plates extending across the chamber in the same plane as the plates 21, 21, their upper and lower ends being tapered.

In the modification shown in Fig. 5, the plates 21 and 22 are replaced by plates 23, 23, extending from the top to the bottom of the chambers within the shell 10.

In the modification shown in Fig. 6, the plates 22, 22 are replaced by plates 24, 24 which extend downwardly beyond the lower portion of the chambers within the shell 10 into the chamber of the rotary pump 12.

In the modification shown in Figs. 7 and 8, the foraminous plates 14 and 17 are formed of square bars 41, 41, so situated that the openings 42, 42 between the bars 41, 41, 10 diverge upwardly and downwardly.

In the modification shown in Figs. 9 and 10, the foraminous plates 14 and 17 are formed of round bars 43, 43, to allow of the divergent openings 44, 44.

15 A perforated steam pipe 25 is introduced into the chamber formed by the shell 8.

In order to facilitate reference to the various chambers, they will hereafter be referred to as the top chamber 26, the dyeing chamber 27, the liquor supply chamber 28, the plate chamber 29, and the pump chamber 30.

An over-flow pipe 31 connects the top chamber 26 with the centrifugal pump 12 to 25 allow of continuous flow of the liquor upwardly through the machine.

A pipe 32 connects the pump 12, with a liquor supply tank, not shown, the pipe 32 carrying the valve 33.

30 A pipe 34, 35 extends from within the liquor supply chamber 28 to a point above the top chamber 26, and carries a thermometer 36 for determining the temperature passing through the pipe 34, 35.

35 A sample dyeing machine 37, exactly similar to the above described dyeing machine, except in smaller proportions, is connected to the liquor supply chamber 28 by the pipe 38 and to the top chamber 26 by the pipe 39. The sample material in the machine 37 is examined by removing the top 40 which is threaded to the sample machine 37.

The operation of the device is as follows: 45 The annular member 18 and the foraminous plate 17 are removed, the goods to be treated introduced into the dyeing chamber 27, the plate 17 replaced and pressed down upon the goods by means of the member 18.

50 A small quantity of the same goods is placed in the sample device 37. The pump 12 is started and the valve 33 opened, allowing the liquor to flow through the pipe 32 into the pump 12, by which it is forced upwardly through the pump chamber 30, the plate chamber 29, the liquor supply chamber 28, and the goods in the dyeing chamber 27, into the top member 26. When the liquor has reached a height to allow its flow 55 through the pipe 31 back into the pump 12, the valve 33 is closed and the liquor is forced continuously through the device as above stated.

From time to time, the pump 12 is stopped, the top 40 is removed for the purpose

of examining the condition of the dyeing operation, and is then replaced, the pump 12 started and the dyeing continued until it has reached a satisfactory condition.

It is evident that during this operation 70 the liquor is forced upwardly through the plates 22, 22, the upper edges of which cause it to spread out upon leaving the space between the plates, the same result being obtained as the liquor leaves the spaces 75 between the plates 21, 21. As the liquor leaves the spaces in the foraminous plate 16, the divergent edges of the separating members, causes it to spread out and to impinge upon the material in the dyeing chamber 27 80 in a practically uniform manner, and that the continuing of this flow will force the liquor throughout the mass of goods, and will prevent the formation of channels 85 through the goods. As the plate 17 is the same as plate 16, the pressure will be maintained in the dyeing chamber 27, and the liquor will be compelled to penetrate the goods inwardly toward each of the openings 90 in order to escape.

I do not limit myself to the size, shape, 95 number or arrangement of parts as shown and described, all of which may be varied without going beyond the scope of my invention as described and claimed.

What is claimed, is:

1. In a dyeing machine, in combination, a receptacle having imperforate sides, a foraminous plate having elongated divergent openings within the receptacle, a second foraminous plate having elongated divergent openings within the receptacle, a fiber chamber comprising the space between the plates and the imperforate sides of the receptacle, means for maintaining the two plates at 100 varying distances from each other and capable of compressing fiber between the plates and the imperforate sides of the receptacle, a liquid supply chamber below the first plate, a downwardly converging plate-carrying chamber, upwardly divergent plates within the plate-carrying chamber and means for forcing a liquid upwardly between the plates in the plate-carrying chamber and through the fiber chamber. 110

2. In a dyeing machine, in combination, a receptacle, a foraminous plate carrying elongated upwardly divergent openings within the receptacle and fixedly attached thereto, a second foraminous plate carrying elongated downwardly divergent openings within the receptacle and above the first plate, means for moving the plates with respect to each other, means for maintaining the plates in a predetermined position, a liquid supply chamber below the first plate, a downwardly converging plate-carrying chamber, a series of plates within the plate-carrying chamber, the edges of said plates being tapered, means for heating a liquid 120 125 130

within the receptacle and means for forcing a liquid through the receptacle.

3. In a dyeing machine, in combination, a receptacle having imperforate sides, a foraminous plate having elongated upwardly diverging openings within the receptacle, a second foraminous plate having elongated downwardly divergent openings within the receptacle, a fiber chamber comprising the space between the plates and the imperforate sides of the receptacle, means for maintaining the two plates at varying distances from each other and capable of compressing fiber between the plates and the imperforate sides of the receptacle, a liquid supply chamber below the first plate, a downwardly converging plate-carrying chamber, upwardly divergent plates having tapered edges within the plate-carrying chamber, means for heating a liquid within the receptacle, means for forcing a liquid upwardly through the plate-carrying chamber, the liquid supply chamber and the fiber chamber and means for returning the liquid from above the top foraminous plate to allow of its continuous circulation through the device.

4. In a dyeing machine, in combination, a receptacle having imperforate sides, a foraminous plate comprising a series of parallel divergent-shaped bars, a second foraminous plate comprising a series of parallel divergent-shaped bars, means for maintaining the two foraminous plates at varying distances from each other, a fiber chamber between the two plates and the sides of the receptacle, a liquid supply chamber below the lower foraminous plate, an upwardly divergent plate-carrying chamber below the liquid supply chamber, a series of upwardly divergent plates within the plate-carrying chamber, a pump connected with the lower portion of the plate-carrying chamber, and means connecting the upper portion of the receptacle with the pump to allow of a continuous circulation of a liquid through the device.

5. In a dyeing machine, in combination, a receptacle having imperforate sides, a foraminous plate having elongated divergent openings within the receptacle, a second foraminous plate having elongated divergent openings within the receptacle, a fiber chamber comprising the space between the plates and the imperforate sides of the receptacle, means for maintaining the two plates at varying distances from each other and capable of compressing fiber between the plates and the imperforate sides of the receptacle, a liquid supply chamber below the first plate, a downwardly converging plate-carrying chamber, upwardly divergent plates within the plate-carrying chamber, a smaller testing device similar and proportionate to, and exterior to, the larger device.

vice, means for connecting the spaces below the lower foraminous plates to allow of the flow of a liquid and means for passing a liquid through said spaces, the connecting means, the first plates, the fiber chambers 70 and the second plates.

6. In a dyeing machine, in combination, a receptacle, a foraminous plate carrying elongated upwardly divergent openings within the receptacle and fixedly attached thereto, a second foraminous plate carrying elongated downwardly divergent openings within the receptacle and above the first plate, means for moving the plates with respect to each other, means for maintaining the plates in a predetermined position, a liquid supply chamber below the first plate, a downwardly converging plate-carrying chamber, a series of plates within the plate-carrying chamber, means for heating a liquid within the receptacle, a smaller testing device similar and proportionate to, and exterior to, the larger device, means for connecting the spaces below the lower foraminous plates to allow of the flow of a liquid 80 and means for passing a liquid through said spaces, the connecting means, the first plates, 90 the fiber chambers and the second plates.

7. In a dyeing machine, in combination, a receptacle having imperforate sides, a foraminous plate having elongated upwardly divergent openings within the receptacle, a second foraminous plate having elongated downwardly divergent openings within the receptacle, a fiber chamber comprising the space between the plates and the imperforate sides of the receptacle, a liquid supply chamber below the first plate, a downwardly converging plate-carrying chamber, upwardly divergent plates having tapered edges within the plate-carrying chamber, means for heating a liquid within the receptacle, a smaller testing device similar and proportionate to, and exterior to, the larger device, 100 means for connecting the two liquid supply chambers, and means for forcing a liquid 105 upwardly between the plates in the plate-carrying chambers and through the liquid supply chambers, the bottom foraminous plates, the fiber chambers and the upper foraminous plates.

8. In a dyeing machine, in combination, a receptacle having imperforate sides, a foraminous plate comprising a series of parallel divergent-shaped bars, a second foraminous plate comprising a series of parallel divergent-shaped bars, means for maintaining the two foraminous plates at varying distances from each other, a fiber chamber between the two plates and the sides of the receptacle, a liquid supply chamber below 125 the receptacle, a smaller testing device similar and proportionate to, and exterior to, the larger device.

the lower foraminous plate, an upwardly divergent plate-carrying chamber below the liquid supply chamber, a series of upwardly divergent plates within the plate-carrying chamber, a pump connected with the lower portion of the plate-carrying chamber, means connecting the upper portion of the receptacle with the pump to allow of a continuous circulation of a liquid through the device, a smaller testing device similar and proportionate to, and exterior to, the

larger device, means for connecting the two liquid supply chambers, and means for forcing a liquid upwardly between the plates in the plate-carrying chambers and through the liquid supply chambers, the bottom foraminous plates, the fiber chambers and the upper foraminous plates. 15

Signed at New York city in the county of New York and State of New York this 20 26th day of December 1916.

HOWARD M. DUDLEY.
